UNITED STATES PATENT OFFICE

162,357

BAKING PAN

Joseph Sobel, Camden, N. J.

Application December 5, 1949, Serial No. 6,411

Term of patent 3½ years

(Cl. D44—1)

To all whom it may concern:

Be it known that I, Joseph Sobel, a citizen of the United States, residing at Camden, State of New Jersey, have invented a new, original, and ornamental Design for a Baking Pan, of which the following is a specification, reference being had to the accompanying drawing forming a part hereof.

Fig. 1 is a top plan view of a baking pan showing my new design;

Fig. 2 is a vertical longitudinal sectional view on the line 2—2 of Fig. 1; and

Fig. 3 is a vertical transverse sectional view on the line 3—3 of Fig. 1.

I claim:

The ornamental design for a baking pan, substantially as shown.

JOSEPH SOBEL.
